UNITED STATES PATENT OFFICE.

BENEDETTO REA, OF BOSTON, MASSACHUSETTS.

DESIGN FOR AN ICE-CREAM CORNUCOPIA.

40,739.

Specification for Design. Patented June 21, 1910.

Application filed May 27, 1909. Serial No. 498,774. Term of patent 7 years.

To all whom it may concern:

Be it known that I, BENEDETTO REA, a subject of the King of Italy, (having filed my intention of becoming a citizen of the United States,) residing at Boston, in the county of Suffolk and State of Massachusetts, have invented a new, original, and ornamental Design for Ice-Cream Cornucopias, of which the following is a specification, reference being had to the accompanying drawing, forming part thereof.

The figure is a perspective view of an ice-cream cornucopia showing my new design.

I claim:

The ornamental design for an ice-cream cornucopia, as shown.
